UNITED STATES PATENT OFFICE.

HARRY S. STANSBURY, OF MONKTON, MARYLAND, ASSIGNOR OF ONE-HALF TO HARRY I. ROWE, OF BALTIMORE, MARYLAND.

GREASE-GUN.

1,330,728.

Specification of Letters Patent. Patented Feb. 10, 1920.

Application filed June 26, 1918. Serial No. 242,086.

To all whom it may concern:

Be it known that I, HARRY S. STANSBURY, a citizen of the United States, residing at Monkton, in the county of Baltimore and 5 State of Maryland, have invented certain new and useful Improvements in Grease-Guns; and I do hereby declare the following to be a full, clear, and exact description of the invention, such as will enable others 10 skilled in the art to which it appertains to make and use the same.

This invention relates to improvements in grease guns of the character employing a barrel having a filling slot, and surrounded 15 by a sleeve, and has for one of its objects the provision of means for drawing the barrel within the sleeve by the piston and its handle, so that the parts of the device will be positioned to discharge the grease on 20 pushing the handle of the piston.

Another object of this invention is the provision of means in the sleeve adapted to close the filling slot in the barrel and prevent the grease from working behind the 25 piston when the barrel is drawn in the sleeve.

A further object of this invention is the provision of a grease gun of the above-stated character, which will be simple, durable and efficient, and which may be manufactured and sold at a comparatively low 30 cost.

With these and other objects in view, as will become more apparent as the description proceeds, the invention consists in certain novel features of construction, combination and arrangement of parts as will be hereinafter more fully described and claimed.

40 For a complete understanding of my invention, reference will be had to the following description and accompanying drawing, in which:

Figure 1 is a side elevation, partly in section, of a grease gun constructed in accordance with my invention, and illustrating the barrel extended exteriorly of the sleeve ready to receive the grease.

Fig. 2 is a vertical sectional view of the 50 grease gun in position ready to discharge the grease.

Fig. 3 is a transverse sectional view, taken on the line 3—3 of Fig. 2.

Fig. 4 is a similar view, taken on the line 4—4 of Fig. 2.

Referring in detail to the drawing, the numeral 1 indicates a barrel, having a longitudinally filling slot 2. One end of the barrel 1 has secured thereto a nozzle 3, provided with screw threads 4 for receiving a tube or pipe to permit the same to be readily inserted within the opening of a bearing or other device to be lubricated. The band 4' surrounds this end of the barrel to reinforce the same and is located within the nozzle 55 and secured thereto and to the barrel. The other end of the barrel 1 has secured therein a combined reinforcing ring and stop 5. The barrel 2 is surrounded by a sliding sleeve 6, having one of its ends closed by a cap 7, provided with an opening to receive a piston rod 8. The piston rod 8 has a handle 9 formed upon its outer end, while its inner end has secured thereto a piston 10. The piston 10 is located within the barrel 2 in 60 advance of the combined reinforcing ring and stop 5, and consists of a metallic plate 70 11 and a pair of disks 12, constructed of leather or other material suitable for the purpose.

A closure strip 13 is secured to the inner face of the sleeve 6 adjacent each end thereof, and is slightly offset from the inner face thereof so that the same will slide into the filling slot 2 when the barrel is moved 75 within the sleeve, thereby closing the filling slot. The closure strip 13 is of such a width that when disposed within the slot 2 it engages the walls thereof and prevents grease 80 from escaping from the barrel and behind 90 the piston.

In operation the barrel 1 is extended outwardly of the sleeve 6, as illustrated in Fig. 1, and is filled with grease through the filling slot 2. The operator then pulls upon the handle 9, drawing the barrel 2 within the sleeve to a position occupied as illustrated in Fig. 2. As the barrel moves within the sleeve, the closure strip 13 closes the filling slot 2 and prevents grease from escaping 100 95 therefrom and also working behind the piston. The device is then ready to discharge the lubricant by shoving the piston forwardly in the usual manner.

While I have shown and described the 105 preferred embodiment of my invention, it

will be understood that minor changes in construction, combination and arrangement of parts may be made without departing from the spirit and scope of the invention 5 as claimed.

Having thus described my invention, what I claim is:

A grease gun comprising a cylindrical barrel having a longitudinally extending 10 filling slot, a nozzle secured to one end of the barrel, a combined stop and reinforcing ring secured in the other end of the barrel, a cylindrical sleeve having one end closed and slidably receiving the barrel, a piston in 15 said barrel, a rod connected to the piston

and extending through the sleeve and the closed end thereof, and a closure strip secured to the inner face of the sleeve adjacent each end thereof and adapted to close the filling slot when the barrel is drawn into 20 the sleeve by the piston engaging the stop and pulling upon the rod.

In testimony whereof I affix my signature in presence of witnesses:

HARRY S. STANSBURY.

Witnesses:

W. GILL PRIEST,
WILLIAM GRASON,
C. MARLEY HIPSLEY.
